(57) **CLAIM**

We claim the ornamental design for a air compressor assembly, as shown.

DESCRIPTION

FIG. 1 is an isometric view showing my new design, with environment shown;

FIG. 2 is an isometric view thereof;

FIG. 3 is a front elevation view thereof;

FIG. 4 is a left side elevation view thereof;

FIG. 5 is a right side elevation view thereof;

FIG. 6 is a rear elevation view thereof;

FIG. 7 is a top plan view thereof;

FIG. 8 is a bottom plan view thereof;

FIG. 9 is an isometric view thereof, with air compressor shown separated from tank; and,

FIG. 10 is an isometric view thereof with environment shown, and with air compressor shown separated from tank.
